UNITED STATES PATENT OFFICE.

MORTIMER F. FLYNN, OF WEST NEW BRIGHTON, NEW YORK, ASSIGNOR TO NEW NAP SYSTEM, INC., OF NEW YORK, N. Y., A CORPORATION OF NEW YORK.

APPARATUS FOR RECONDITIONING FELTS OF PAPER-MAKING MACHINES.

Application filed August 11, 1925. Serial No. 49,676.

This invention relates to the apparatus for re-conditioning felts of paper making machines and the like.

In the manufacture of paper in the various types of so-called paper making machines, the pulp after treatment as desired is fed to so-called groups of dehydrating presses or like units, each group of dehydrating presses embodying one or more sets of couch rollers and other forms of presser rolls through which the paper pulp is fed and transferred from stage to stage by means of a so-called felt, preferably a blanket conveyer formed of wool fibre, the nap and body or woven structure of which are of a form for properly performing the functions of feeding and transferring the paper pulp as aforesaid and to permit the passage therethrough of the water pressed from the paper pulp by the action of the couch rolls and presser rolls. The speed of travel of the felts of dehydrating units of paper making machines varies from three hundred to fifteen hundred feet and upwards per minute.

In such function of the felts, the nap of the felt becomes reduced in height and the fibres of the nap matted or otherwise displaced relative to one another, and in course of time become worn or otherwise deformed and particles of the paper pulp more or less fill up the nap and the interstices between the warp and weft threads of the body or woven structure of the felt. It has been the practice heretofore to interrupt the operation of the paper making machine in the effort to remove the pulp particles from the interstices of the felt. The methods heretofore practiced are known as the "roping", "beater" and "spreading" methods.

The "roping" method consists of drawing the felt to one side of the rolls so that it hangs loosely on the rolls, then spraying the felt with water in the attempt to wash out the paper pulp. Such "roping" method is not successful for the reason that the occluded paper pulp is not effectually removed and the method does not contribute whatsoever toward re-conditioning of the nap of the felt.

The "beater" method requires the provision of rotating paddles that are set at an angle to the travel of the felt to cause the arms of the paddles to strike the felt, which

method but partly loosens the pulp and wears the nap and greatly deforms the woven structure.

The "spreading" method necessitates the use of so-called "spread" rolls which are mounted on the paper making machine and comprise a two-section roll, each section being one-half of the length of the felt roll. Each spread roll is mounted on pillow blocks immediately under the felt and at an angle to the travel of the felt to thereby position the respective sections of each spread roll to diverge from the center of the felt toward the opposite ends of the felt. The "spreading" method causes the felt to be spread from its center towards its opposite ends, so to speak, to stretch the felt, in the effort to open up the weave and allow the water and moisture to be pressed through by the couch rolls. This procedure is highly disadvantageous in that it increases the width of the felt, necessitating trimming at the edges to restore it to the required width, and enlarges the mesh of the weave, thus rendering the felt more susceptible of occluding the paper pulp.

All of the above previous methods are ineffectual in restoring the nap of the felt and the respective treatments of the prior art subject the felt to distortionary strains, greatly shortening the life of the felt. As a result, the average life of a felt for the first dehydrating unit is but eighteen days and the range of life of the felt of the second and subsequent dehydrating units is from forty to fifty days.

Pursuant to my invention, the felt is treated by means of a set of pointed members, the free ends of which are arranged to penetrate through the surface of the felt and more or less within the body or woven structure of the felt and upon the withdrawal of the free ends of the members from the felt, the nap of the felt is restored and the occluded paper pulp is removed from the interstices of the woven structure. The opposite ends of the pointed members are mounted on a suitable support for locating the free ends of the members in a predetermined relation to the path of travel of the felt, to attain the effectual penetration and withdrawal of the members as described.

My method and apparatus are of a form to effect the application of my invention to

the felt of a paper making machine while the machine is in operation in the making of paper, whereby the renapping of the felt, the removal of the paper pulp and other reconditioning processes of the felt take place without shutting down the paper making machine. If desired, the re-conditioning pursuant to my invention may be carried out during the idle or interrupted periods of the paper making machine.

Preferably, my invention is carried out by the use of a re-conditioning device comprising a set of bristles of wire, and provided with burrs at their free ends, the opposite ends of the bristles being mounted in a cylindrical roller, to provide for rotational movement of the pointed members.

The cylindrical roller is positioned in a predetermined relation to the path of travel of the felt. The burrs of the bristles are preferably at an obtuse angle to the direction of length of the respective bristles and the bristles are preferably mounted in the cylindrical roller at an angle to the radial direction of the cylindrical roller. The rotation of the pointed members relative to the axis of the cylindrical roller may be effected by the drag of the free ends of the pointed members in the felt. If desired, the pointed members may be rotated by positive drive, as by gearing from the driving or a driven shaft of the paper making machines proper.

My re-conditioning device is preferably mounted to be moved to its non-operative position by the operation of a lever or other readily accessible means. My re-conditioning device may be of a width materially less than the width of the felt, in which event the device is mounted to be displaced laterally of the direction of travel of the felt and thus be brought into contact with the respective laterally disposed portions of the felt successively, as by means of a worm drive for such lateral displacement and automatic means for returning the reconditioning device in the reversed lateral movement.

Further features and objects of the invention will be more fully understood from the following detail description and the accompanying drawings, in which

Fig. 1 is a side elevation of a Fourdrinier type of paper making machine combined with my invention and illustrating one form of carrying out my method;

Fig. 2 is a detail side elevation, on a greatly enlarged scale showing one form of application of my invention to a felt of a paper making machine of the type indicated in Fig. 1, certain of the parts being omitted to show otherwise hidden parts;

Fig. 3 is a sectional elevation on line 3—3 of Fig. 2;

Fig. 4 is a top plan view of Fig. 2;

Fig. 5 is a sectional elevation on line 5—5 of Fig. 4; and

Fig. 6 is a diagrammatic view on an enlarged scale illustrating the re-conditioning of the felt.

In the drawings of my application, as above indicated, the paper making machine is of the Fourdrinier type. However, it will be understood that the paper making machines employed in this country and other active paper making countries are modified more or less in special design, but adhere to the fundamental principles of the use of two or more so-called groups of dehydrating presses to which the paper pulp is supplied successively from the pulp agitating or treating vat by a screen conveyer belt.

The screen conveyer belt passes between the set of couch rollers of the first dehydrating group, thereby compressing the paper pulp to a sheet-like form which is partially dehydrated and which is passed from the pair of couch rollers of the first dehydrating group to its felt and thereafter passed through the one or more sets of presser rollers thence to the pair of couch rollers of the second dehydrating group and similarly through the second dehydrating group to the third dehydrating group and for any additional or similar groups of dehydrating presses.

Such passage of the sheet-like mass of paper pulp ensues through each group of dehydrating presses by means of a conveyer known in the trade as a felt, and which is substantially universally a woolen blanket formed of a warp and weft woven structure of substantially pure wool fibre and provided with a nap of a predetermined thickness and other characteristics for attaining the purposes desired.

From the dehydrating groups, the sheet-like mass of pulp is passed to the drying "rooms" consisting of the desired number of drying units, each having its sets of upper and lower rolls between which a belt of canvas or like material passes for conveying the sheet-like mass of pulp through the various heating and calendering rolls and for transference to the next unit, and finally to a winding reel.

In Fig. 1, the screen belt is indicated at 10 and the paper pulp is conveyed by the screen 10 through the pair of couch rollers 11, 12. The partially formed "sheet" of pressed, partially dehydrated mass of paper pulp, discharged from the screen 10 after passage through the couch rollers 11, 12, is indicated at 13, which is passed onto the upper surface of the felt 14. The felt 14 passes in its transit through the pair of presser rolls 15, 16 and conveys the sheeted mass of paper pulp therethrough for further dehydration. The felt 14 further transfers the sheeted mass of paper pulp to the general location indicated at 17 where the sheeted mass of paper pulp indicated at 13a passes

- over the desired number of idlers 18, onto the felt 19 and thence through the set of couch rollers 20, 21. The sheeted mass of paper pulp, thus further dehydrated and 5 further sheeted passes from the felt 19 at the general location indicated at 22 from the felt 19, thence over the desired number of idlers 23 onto the felt 24 of the next dehydrating unit. It will be understood that 10 in the transfer of the sheeted mass through the respective parts of the first dehydrating group, the felt 14 and the felt 19 are suitably driven by frictional contact with the desired friction driving rolls pursuant to 15 approved practice and with the necessary number of idlers and pulleys and other necessary appurtenances are employed to maintain the desired tension or tautness of the felt.
- 20 My re-conditioning device is mounted on the first dehydrating group at any suitable location and in predetermined relation to the felt 14, and similarly with respect to the felt 19. As one suitable location relative 25 to the felt 14, I have indicated in Fig. 1 the location 25, namely within a range of travel of the felt 14 which is exteriorly of the path of travel of the sheeted paper pulp. Such location 25 is advantageous for the 30 reason that the upper and effective surface of the felt 14 is available to contact from above by my re-conditioning device and the introduction of my re-conditioning device thereat does not interfere with the movement of the working parts of the paper 35 making machine proper nor restrict the access to the same. The particular construction of the preferred forms of my re-conditioning device are set forth more fully hereinafter.
- 40 Returning to the further travel of the sheeted mass 13^b, onto the felt 24 of the second group of dehydrating presses, the sheeted mass 13^b is passed from the pair of couch rolls 11^a, 12^a, similarly as the aforesaid couch rolls 11, 12, thence transferred by the conveying felt 24 to the general location 17^a to transfer the sheeted mass 13^c about the press rollers 18^a onto the felt 19^a 45 through the pair of couch rollers 20^a, 21^a, from whence the sheeted mass 13^d passes over the idler 23^a to the third group of dehydrating presses, indicated at the bottom 50 of Sheet 1, onto the felt 27 of the third group 55 of dehydrating presses. My re-conditioning device 26^a for the second group of dehydrating presses is indicated as disposed at the general location 25^a relative to the felt 24.
- 60 In like manner, the sheeted mass 13^d is conveyed through the pair of couch rollers and presser roller of the third group of dehydrating presses and transferred onto the felt 28 of the third group of dehydrating presses, the parts of the third group of dehydrating presses correspondingly substan-
- tially to the parts of the aforesaid groups. My device 26^b for the third group is indicated at 25^b. In like manner, the fourth or additional group of dehydrating presses 70 may be employed.
- 75 After the desired degree of dehydration has been carried out, the final sheeted mass of paper pulp, indicated at 13^e in Fig. 1, is passed to the drying units 29^a, 29^b, etc. of the desired number of heating units such as the rotating drums 30^a, 30^b, 30^c, 30^d, 30^e, whereby the sheeted mass 13^e is brought in direct contact with the periphery of the hollow drums such as the drums 30^a and 30^b, or conjointly by the use of a belt 31, under suitable tension and exteriorly of the sheeted mass to attain the desired ultimate dehydration and state of dryness. The belt 31 is usually of canvas but may be of any desired material, and if of wool, may be provided with a re-conditioning device similarly as aforesaid.
- 80 As one form of a re-conditioning device embodying my invention, I have illustrated in Figs. 2 to 6, the re-conditioning device 26 as applied to the felt 14 of the first group of dehydrating presses indicated in Fig. 1. At the location 25, the felt 14 is travelling in the direction of the arrow 32, about the pulley 33. In such form of my invention, the drive of the pointed members 34 of my re-conditioning device 26 is by contact with the felt 14, i. e., by drag movement therewith, whereby the members 34 are rotated in the direction indicated by the arrow 35. 85 As is illustrated in Fig. 6, the members 34 are preferably disposed at the angle indicated by the arc 36 to the radial direction of the substantially cylindrical base 37. Preferably, the free ends of the members 34 90 are provided with burrs 38 disposed at an obtuse angle relative to the direction of length of the members 34. Such arrangement provides for the ready penetration of the free ends of the members 34 and the burrs 38 thereat within the nap 39 and woven structure or body 40 of the felt 14 at the stage of initial contact of any particular group of members 34 with the felt 14; as is indicated at 41 and upon the continued 95 travel of the felt 14 in the direction of the arrow 32 and the consequent travel of the members 34, their free ends and the burrs penetrate to the desired extent into the woven structure or body 40 of the felt 14 100 as is indicated at the intermediate stage 42. Upon the continued travel of the felt 14 and consequent travel of the members 34 to the stage 43, the free ends of the members 34 105 and the burrs 38 thereat are withdrawn from the body or woven fabric 40 of the felt 14 110 thereby dislodging any paper pulp particles or other foreign matter "filling" the interstices of the woven fabric and bringing the same to and through the nap 39^a and eject- 115
- 120
- 125
- 130

ing the same into the air, as indicated at 44. If desired, the ejected pulp particles 44 may be caught upon a suitable platform or on a belt travelling laterally relative to the direction of travel of the felt 14, or removed by means of a vacuum chamber or by a blast of compressed air, or other suitable means.

In such action of removal of the paper pulp particles, the free ends of the members 34 and the burrs 38 thereat engage the fibres of the warp and weft threads of the body or woven fabric 40 of the felt 14 and thus renap the upper and effective surface of the felt 14 and restore or re-form the nap of the felt 14 at locations which may have been matted or flattened or otherwise deformed, or worn or otherwise rendered defective in the paper making operations.

The location 25 of the character above described is advantageous, by reason of the proximity to the pulley 33 or equivalent, providing for the desirable degree of tautness of the felt 14 and substantial uniformity of path of travel of the felt 14.

25 The optimum relationship of the members 34 relative to the upper or effective surface of the felt 14 is had by mounting the members 34 and their supporting base 37 and the appurtenant parts in the desired predetermined relation from a suitable fixed point 46, such as at the vertical beam 47 of the paper making machine proper or other suitable fixed support, as is set forth more fully hereinafter.

30 Such mounting of the members 34 includes a suitable housing 48 or equivalent. I prefer to provide the bar 49 of abrasive, usually adjustably mounted as hereinafter described, on the housing 48 in suitable relation to the free ends and the burrs 38 of the members 34 to restore the sharpness of any dull burr, restore the angle of any displaced burr, restore the angle of any bristle displaced relative to its support and

45 restore any broken burr. Such bar 49 of abrasive is suitably supported in the housing 48 in the desired relation to the free ends of the members 34 and the burrs 38, as by mounting the bar 49 in the metal frame 50, carried relative to the housing 48 by means of the pins 51; the pins 51 are secured at their inner ends respectively to the metal frame 50 and freely project through suitable openings 53, 54 in the housing 48. The outer ends of the pins 51, 52 are respectively provided with the heads 55. About each pin 51, is coiled an expansive spring 57, one end of which rests upon the housing 48 and the opposite end abuts against the head 55 of

50 the pin. Between the openings 53, 54 of the respective pins 51, I locate the adjusting screw 59 passing through a suitable threaded opening in the housing 48 and provided with a knurled head, whereby upon advancing 55 the adjusting screw 59 the abrasive

bar 49 is set to contact with the free ends and the burrs 38 of the members 34 at any desired regulatable pressure. In such setting, the pins 51, of the housing 48 guide and retain the frame 50 of the abrasive bar 49 and tension the springs 57, 57. Upon loosening the adjusting screw 59, the springs 57, 57 retract the frame 50 and the abrasive bar 49 from contact with the free ends and the burrs 38 of the members 34.

I also prefer to provide suitable rectifying means for the members 34 for restoring the alignment of the members 34 in the event of the displacement of the same ensuing in use, and also for removing any serrations of the flat faces of the burrs which may arise by the action of the abrasive, and thus prevent such serrations from cutting or unduly tearing the fibres of the warp and weft comprising the woven structure of the felt. Such rectifying means may be in the form of a flat bar 63 of steel or other suitable material, adjustably supported relative to the frame 48 similarly to the frame 50 of the abrasive bar 49 and adjustably positioned to contact with the free ends and the burrs 38 of the members 34. To such bar 63 is secured guide and retaining pins 64, similar to the aforesaid pins 51, and passing through suitable openings in the frame 48, about which pins 64 are coiled the expansive springs 65, acting against the heads 66 of such pins 64 and tending to move the bar 63 radially outwardly relative to the free ends of the members 34. The adjusting screw 67, see Fig. 2, passing through a suitable threaded opening in the frame 48, serves to set the position of the bar 63 relative to the free ends and the burrs 38 of the members 34, to attain the desired pressure 100 against the same.

The use of the abrasive 49 and of the rectifying bar 63 may be simultaneous or not as preferred, and the use of the abrasive 49 and of the rectifying bar 63 may be continuous or intermittent.

110 Preferably, the position of the abrasive 49 is in advance of the position of the rectifying bar 63 relative to the path of travel of the burrs 38 of the members 34.

115 As one form of mounting for the set of re-conditioning members 34 and other appurtenant devices carried by the housing 48, I describe the following.

The cylindrical supporting base is in the form of a hollow roller 37 fixedly mounted on its shaft as by end disks 70 or hubs or equivalent. One shaft end 71 extends through the bearings 72 carried by the extension of the housing 48; the pulley 73 is pinned or otherwise secured to such exterior shaft end 71. In a similar manner, the opposite shaft end 74 is mounted in the bearing 75 and the pulley 76 is pinned or otherwise secured to the shaft end 74. For sim- 120 125 130

plicity of assembly, the shaft ends 71, 74 may be non-integral with the body of the shaft and secured by threaded or other connection. The pulleys 73, 76, see Fig. 4, 5 cooperate respectively with the pulleys 77, 78, respectively journaled in the oppositely disposed bearings 80, 81 in the housing 48. The pulleys 77, 78 are respectively secured by the screws 82, 83 passing through threaded openings in the respective collars 82^a, 83^a, 10 to the central retaining collars 77^a, 78^a, respectively. The drive between the pulley 73 and its coating pulley 77 is by means of a belt 84 and the drive between the pulley 76 and its coating pulley 78 is by means of the belt 85, one of which belts 84, 85, is crossed such as the belt 85, whereby upon the travel of the felt 14 in the direction of the arrow 86, as indicated in Fig. 4, corresponding to 15 the direction of the arrow 32 in Fig. 2, as aforesaid, and the consequent rotation of the re-conditioning members 34 in the direction of the arrow 87, Fig. 4, corresponding to the direction of the arrow 35, see Fig. 2, the belt 20 84 travels at its upper length in the direction of the arrow 88, see Fig. 4, whereas the upper length of the belt 85 passing over the pulley 76 travels in the direction of the arrow 89.

30 Associated with the pulley 77 is the clutch 90, and the clutch 91 is associated with the pulley 78, and I combine the clutches 90, 91, whereby upon the closure of one clutch, say the clutch 90 as indicated in Fig. 4, the 35 other clutch 91 is positively moved to and retained in its open position, and vice versa.

As one form of such arrangement of the 40 clutches 90, 91, I fixedly mount the movable clutch member 90^a on the inner shaft 92 and similarly fixedly mount the movable member 91^a of the clutch 91 on the inner shaft 92, whereby the shaft 92 serves as the common clutch shaft. The opposite ends of the clutch shaft 92 are provided with the 45 impact, cushioning springs 95, 96 respectively serving as described more fully hereinafter in cooperation with stops at the opposite ends of the frame of the paper making machine to shift the clutch shaft 92 and thereby throw the movable clutch members 50 90^a, 91^a respectively to their open and closed positions.

Between the collars 82^a and 83^a, I locate the pin 93 secured to the shaft 92 and received within the opposite slots 94 in the hub 95 of the worm 97 which is loosely mounted on the inner shaft 92 and space the worm 97 from the respective collars 82^a and 83^a by the loose collars 96, 96, preferably with intervening roller bearings.

60 The worm 97 meshes with the worm gear 98 mounted on the shaft 99, journaled in suitable oppositely disposed bearings, 100, 100, see also Figs. 2 and 3. The shaft 99 is attained in position by pinning at 98^a the

hub of the worm gear 98 and by means of the collar 101, pinned to the end of the shaft 99 extending beyond the bracket 102 of the housing 48. At the opposite end of the shaft 99 is fixed the gear 103 meshing with the rack 70 104, secured to or machined on the inner vertical face of the guide support 105. The guide support 105 is preferably an I-beam of sufficient strength and rigidity to span from one side of the paper making machine 75 to the opposite side without any substantial sag, the opposite edges 106 of the I-beam 105 being milled to substantially smooth, rectilinear planes, on which travels the set of spaced grooved rollers 107, 108, respectively 80 mounted on the shafts 109, journaled at their opposite ends in the housing 48. To attain enhanced alignment of travel of the housing 48 relative to the I-beam 105, I provide the similar set of spaced, grooved rollers 85 110, 111, respectively on similar shafts 109 for guiding contact with the opposite edges 106^a, of the I-beam 105.

The movement of the group of re-conditioning members 34 from their position of 90 operation of re-conditioning the felt to a position of non-operation may be attained by any desirable means. As one form of such means, the I-beam 105 may be rotatively mounted and set manually or by power. 95 One form of such rotatable mounting may comprise the journal 115 carried by the bracket 116, see Figs. 4 and 2, secured by the bolts 117, 117, to the vertical beam 47 of the paper making machine proper, as 100 aforesaid, or like fixed support. The stud shaft 118 at its inner end is secured to or is integral with the oppositely disposed flat plates 119, 119 bolted, riveted or the like indicated at 120 to one end of the I-beam 105. In a similar manner, the opposite end of the I-beam 105 is provided with a stud shaft 118 and journaled in a bearing (not shown) 105 similar to the aforesaid bearing 115 and 110 similarly fixedly mounted relative to the paper making machine proper.

At one end of the I-beam 105, as at the end illustrated in Fig. 4, the control lever 121 is provided for rotating the I-beam 105, 115 as by pinning as indicated at 122 the hub 123 of the control lever 121 to the stud shaft 118. The control lever 121 is provided with the spring held catch 125 having the handle 126, the dog 127 of the catch 125 cooperating 120 with the notch 128 of the notched plate 129 for holding the control lever 121 and therewith the I-beam 105 in a non-operative position.

Such provision of means affords also adjustable means for setting the re-conditioning members 34 in operative relation to the felt to be re-conditioned, namely, by the provision of the set of notches 127^a for holding the dog 127 of the control lever 121 at 125 130

any desired position within the range of adjustment.

As above indicated, stops are provided at the opposite ends of the path of travel of the housing 48 for shifting automatically the clutch shaft 92 carrying the respective movable clutch members 90^a, 91^a. As one form of such stop, I provide the bracket 116 with the stop 129 of metal secured to or cast with the bearing 115 of the bracket 116, and the cushioning block 130 of rubber or other suitable material positioned by the set screw 131.

As above stated, relative to Fig. 4, assuming the right-hand clutch 90 to be in its closed position and the clutch 91 in its open position the clutch shaft 92 is rotated in the direction of the arrow 132, thereby rotating the worm gear 98 in the direction of the arrow 133, and the shaft 99 of the worm gear 98 in the direction of the arrow 134, see Fig. 3, whereby the gear 103 meshing with the rack 104 displaces the housing 48 and the re-conditioning members 34 in the direction of the arrow 135, namely in the direction toward the stop member 129. Upon the continued travel of the re-conditioning members 34 toward and in contact with the cushion 130 of the stop member 129, the spring 96 of the clutch shaft 92 encounters the stop cushion 130, thereby throwing the clutch 90 to its open position and the clutch 91 to its closed position, the pin 93 of the clutch shaft 92 extending through the slot 94 to actuate the worm 97 in a direction opposite to the arrow 132, thereby reversing the direction of travel of the worm gear 97, i. e., opposite to the arrow 133 and reversing the direction of travel of the housing 48, i. e., opposite to the arrow 135, by the drive of the gear 103 in relation to the rack 104, which reversed direction of lateral displacement of the re-conditioning members 34 continues until the clutch shaft 92 and its cushioning spring 95 encounter the oppositely disposed stop corresponding to the aforesaid stop 129, whereupon the clutch shaft 92 is shifted in the opposite direction to return the housing 48 and the re-conditioning members 34 in the opposite direction of lateral displacement relative to the felt 14.

The bristles 34 or other pointed members for re-conditioning the felt are preferably of metal or like material possessing the required rigidity and resiliency and other characteristics for the purposes desired.

In the operation of my apparatus in carrying out my process, the abrasive means 49, the rectifying means 63 and the power required for displacing the members 34 laterally of the felt, one or more at any time as the case may be, serve as a drag on the members 34 to provide the desired retarding force to effect the desired re-conditioning of the felt.

It will be understood that my method may

be carried out by means of other forms of apparatus and that the re-conditioning process may be carried out for the full width of the felt in lieu of displacing the support of the reconditioning members laterally of the 70 felt.

Preferably, the bristles 34 are distributed substantially uniformly about the cylindrical roller 37, thereby providing for substantial uniformity of re-napping and otherwise re-conditioning of the face of the felt. The uniformity of re-napping and otherwise re-conditioning is also attained by the action of the abrasive means and the rectifying means, each and both. 80

By reason of the engagement of the bar 49 with the free ends of the wire bristles of my re-conditioning cylinder, the degree of retardation or "drag" on the bristles is regulated by the adjusting screw 55 of the bar 49. It will be observed that at each instant, that is to say, for the successive stages of the rotation of the wire bristles as a whole relative to the bar 49 the regulated pressure is applied to the bristles for the full width of 90 the cylinder which at such instant are in contact with the bar 49 and that such pressure is transmitted through the resilient body portions of such bristles 34, thence through the cylinder and thence through the 95 resilient body portions of the bristles 34 which at that instant are in engagement with the fabric 14. Such resilient means of transmission of the retardation or "braking" effected by the bar 49 on the bristles in producing the desired "drag" on the bristles is enhanced by the provision of the bristles extending at an angle to the radius of the roller 37, as is set forth more fully herein as another feature of my invention. 100

A similar regulation of the pressure of retardation or drag on the bristles of my cylinder is had by the bar 63, the other of my bristle rectifying means, which bar 63 is regulated by means of its regulating screw 110 67 and which bar 63 may be set in operation simultaneously with the bar 49 or intermittently as is set forth more fully herein.

In the re-conditioning operation effected by the successive bristles, the fabric tends to displace the bristles and such displacement is compensated or equalized by the engagement of my bristle rectifying means, to wit, the abrasive 49 or the bar 63 with such displaced bristle or bristles, which engagement ensues substantially immediately after such displacement, in which operation of compensation or equalization, the engagement of such displaced bristle or bristles with my bristle rectifying means is opposite 115 in direction to the force applied by the fabric on the bristle in causing such displacement; accordingly, the operation of the bar 49 and similarly of the bar 63 in such compensating or rectifying action is substan- 120 125 130

tially equal in the extent of force and substantially opposite in direction, thus completely carrying out the rectification action.

From the above, it will be apparent that my method and apparatus provide for re-napping and otherwise re-conditioning the felt without necessitating the interruption of the paper making processes. My method and apparatus maintain the felt at optimum conditions of the nap and the immediate removal of the paper pulp particles and other foreign matter from the body of the felt, whereby the re-conditioned portions of the felt are restored to the desired characteristic of readily permitting the discharge through the felt of water and moisture pressed from the sheeted pulp mass in transit through the couch rolls and other presser rolls, thereby maintaining the process of paper making under optimum conditions.

A further advantage of my process resides in obviating any increase of steam pressure in the drying units in the effort to attain an increased rate of dehydration and drying, as is necessary in the practices heretofore carried out, by reason of the filling up of the body of the felt and consequent forming of "wet spots" in the felt and also of reduced drainage of the water and moisture through the felt.

The bristles 34 or equivalent members may be supported by the hollow cylindrical base 37 in the form of tufts, the fixed ends of which are positioned within perforations, as is indicated in Fig. 6, which perforations are inclined to the radius of the cylindrical base 37 at the desired angle indicated by the arc 36. The effective length of the new or re-formed nap and the extent of penetration of the free ends of the members 34 is determined by the angle of presentation of the members 34 to the surface of the felt or the like to be reconditioned, conjointly with the regulation of the position of the cylindrical base or other support of the members relative to the line of travel or position of the felt and to the degree of drag on the free ends of the bristles.

It will be understood that my process and apparatus is applicable for any form of relative movement between the re-conditioning members and the felt or the like, and including maintaining the felt in a stationary position and bodily moving the housing or other support of the group of re-conditioning members longitudinally or otherwise relative to the felt.

It will be perceived that my invention is also applicable for re-napping fabrics other than felts of wool or the like of paper making machines and the like by similar procedure.

Whereas, I have described my invention by reference to specific forms thereof, it will be understood that many changes and modi-

fications may be made without departing from the spirit of the invention.

I claim:

1. The combination with a paper making machine having a conveyer of felt, rollers for supporting, guiding and driving said felt conveyer and a frame for rotatively supporting said rollers, of a track secured fixedly relative to said frame, a napping cylinder having a width less than the width of said felt conveyer, means for supporting said napping cylinder from said track to locate the ends of the bristles of said napping cylinder within the woven structure of said felt conveyer, and gearing means for moving said napping cylinder along said track transversely of said felt conveyer upon the longitudinal movement of said felt conveyer and the engagement of the bristles of said napping cylinder with said felt conveyer.

2. The combination with a paper making machine having a conveyer of felt, rollers for supporting, guiding and driving said felt conveyer and a frame for rotatively supporting said rollers, of a track secured fixedly relative to said frame, a napping cylinder having a width less than the width of said felt conveyer, adjustable means for supporting said napping cylinder from said track to thereby adjustably locate the ends of the bristles of said napping cylinder within the woven structure of said felt conveyer, and gearing means for moving said napping cylinder along said track transversely of said felt conveyer upon the longitudinal movement of said felt conveyer and the engagement of the bristles of said napping cylinder with said felt conveyer.

3. The combination with a paper making machine having a conveyer of felt, rollers for supporting, guiding and driving said felt conveyer and a frame for rotatively supporting said rollers, of a track secured fixedly relative to said frame, a napping cylinder having a width less than the width of said felt conveyer, means for supporting said napping cylinder from said track to locate the ends of the bristles of said napping cylinder within the woven structure of said felt conveyer, means for moving said napping cylinder from operative position relative with said felt conveyer to non-operative position and for restoring said napping cylinder to operative position and gearing means for moving said napping cylinder along said track transversely of said felt conveyer upon the longitudinal movement of said felt conveyer and the engagement of the bristles of said napping cylinder with said felt conveyer.

4. The combination with a paper making machine having a conveyer of felt, rollers for supporting, guiding and driving said felt conveyer and a frame for rotatively support-

ing said rollers, of a track secured fixedly relative to said frame, a napping cylinder having a width less than the width of said felt conveyer, means for supporting said napping cylinder from said track to locate the ends of the bristles of said napping cylinder within the woven structure of said felt conveyer, means for moving said napping cylinder from operative position relative 5 to said felt conveyer to non-operative position and for restoring said napping cylinder to its adjusted operative position and gearing means for moving said napping cylinder along said track transversely of said 10 felt conveyer upon the longitudinal movement of said felt conveyer and the engagement of the bristles of said napping cylinder with said felt conveyer.

5. The combination with a paper making machine having a conveyer of felt, rollers for supporting, guiding and driving said felt conveyer and a frame for rotatively supporting said rollers, of a track secured fixedly relative to said frame, a napping cylinder 20 having a width less than the width of said felt conveyer, means for supporting said napping cylinder from said track to locate the ends of the bristles of said napping cylinder within the woven structure of said 25 felt conveyer, gearing means for moving said napping cylinder along said track transversely of said felt conveyer upon the longitudinal movement of said felt conveyer and the engagement of the bristles of said napping cylinder with said felt conveyer, and means for reversing the movement of said napping cylinder relative to 30 said track upon said napping cylinder attaining engagement with the lateral edge portions of said felt conveyer.

35 6. The combination with a paper making machine having a conveyer of felt, rollers for supporting, guiding and driving said felt conveyer and a frame for rotatively supporting said rollers, of a track secured fixedly relative to said frame, a napping cylinder 40 having a width less than the width of said felt conveyer, adjustable means for supporting said napping cylinder from said track to thereby adjustably locate the ends of the 45 bristles of said napping cylinder within the woven structure of said felt conveyer, gearing means for moving said napping cylinder along said track transversely of said felt conveyer upon the longitudinal movement of said 50 felt conveyer and the engagement of the bristles of said napping cylinder with said felt conveyer, and means for reversing the movement of said napping cylinder relative to said track upon said napping cylinder attaining engagement with the lateral edge portions of said felt conveyer.

55 7. The combination with a paper making machine having a conveyer of felt, rollers for supporting, guiding and driving said

felt conveyer and a frame for rotatively supporting said rollers, of a track secured fixedly relative to said frame, a napping cylinder having a width less than the width of said felt conveyer, means for supporting said napping cylinder from said track to locate the ends of the bristles of said napping cylinder within the woven structure of said felt conveyer, means for moving said napping cylinder from operative position relative 75 to said felt conveyer to non-operative position and for restoring said napping cylinder to operative position, gearing means for moving said napping cylinder along said track transversely of said felt conveyer upon 80 the longitudinal movement of said felt conveyer and the engagement of the bristles of said napping cylinder with said felt conveyer, and means for reversing the movement of said napping cylinder relative to 85 said track upon said napping cylinder attaining engagement with the lateral edge portions of said felt conveyer.

8. The combination with a paper making machine having a conveyer of felt, rollers for supporting, guiding and driving said felt conveyer and a frame for rotatively supporting said rollers, of a track secured fixedly relative to said frame, a napping cylinder having a width less than the width of said felt conveyer, means for supporting said napping cylinder from said track to locate the ends of the bristles of said napping cylinder within the woven structure of said felt conveyer, means for moving said napping cylinder from operative position relative 90 to said felt conveyer to non-operative position and for restoring said napping cylinder to its adjusted operative position, gearing means for moving said napping cylinder along said track transversely of said felt conveyer upon the longitudinal movement of said felt conveyer and the engagement of the bristles of said napping cylinder with said felt conveyer, and means for reversing the movement of said napping cylinder relative to 95 said track upon said napping cylinder attaining engagement with the lateral edge portions of said felt conveyer.

9. The combination with a paper making machine having a felt conveyer, rollers for supporting, guiding and driving said felt conveyer and a frame for rotatively mounting said rollers, of a napping cylinder having a width less than the width of said felt conveyer, means supported by said frame and extending transversely of the direction of travel of said felt conveyer for supporting and guiding said napping cylinder in its travel transversely of the direction of travel of said felt conveyer, and adjustable means for regulating the extent of penetration of the bristles of said napping cylinder into the woven fabric of said felt conveyer.

10. The combination with a paper making 130

- machine having a conveyer of felt, rollers for supporting, guiding and driving said felt conveyer and a frame for rotatively supporting said rollers, of a transverse track secured relative to said frame, a napping cylinder having a width less than the width of said felt conveyer, means for supporting said napping cylinder from said track to locate the ends of the bristles of said napping cylinder within the woven structure of said felt conveyer, and gearing means for moving said napping cylinder along said track transversely of said felt conveyer upon the longitudinal movement of said felt conveyer and the engagement of the bristles of said napping cylinder with said felt conveyer, and means for reversing the movement of said napping cylinder relative to said track upon said napping cylinder attaining engagement with the lateral edge portions of said felt conveyer. 35

11. The combination with a paper making machine having a conveyer of felt, rollers for supporting, guiding and driving said felt conveyer and a frame for rotatively supporting said rollers, of a transverse track secured relative to said frame, a napping cylinder having a width less than the width of said felt conveyer, means for supporting said napping cylinder from said track to locate the ends of the bristles of said napping cylinder within the woven structure of said felt conveyer, means for moving said napping cylinder from operative position relative to said felt conveyer to non-operative position and for restoring said napping cylinder to operative position, gearing means for moving said napping cylinder along said track transversely of said felt conveyer upon the longitudinal movement of said felt conveyer and the engagement of the bristles of said napping cylinder with said felt conveyer, and means for reversing the movement of said napping cylinder relative to said track upon said napping cylinder attaining engagement with the lateral edge portions of said felt conveyer. 35
12. The combination with a paper making machine having a felt conveyer, rollers for supporting, guiding and driving said felt conveyer and a frame for rotatively mounting said rollers, of a napping cylinder having a width less than the width of said felt conveyer, means supported by said frame and extending transversely of the direction of travel of said felt conveyer for supporting and guiding said napping cylinder in its travel transversely of the direction of travel of said felt conveyer, means for moving said napping cylinder, means for throwing said napping cylinder from operative position relative to said felt conveyer to non-operative position and for restoring said napping cylinder to operative position, and adjustable means for regulating the extent of penetration of the bristles of said napping cylinder into the woven fabric of said felt conveyer. 55
- In testimony whereof I have signed this 65 specification this 8th day of August, 1925.

MORTIMER F. FLYNN.
